UNITED STATES PATENT OFFICE.

RICHARD NICKEL, OF POTSDAM, GERMANY.

APPARATUS FOR MANUFACTURING ENDLESS GRINDING BANDS.

Application filed February 4, 1925, Serial No. 6,906, and in Germany June 23, 1924.

The endless grinding or so-called sanding bands employed now-a-days in many branches of industry are manufactured in this way that bands provided with a layer or coating of the respective abrasive, such as carborundum, corundum, emery, glass, flint, or the like, and consisting of a fabric, paper, leather, or the like, are turned into endless bands by connecting the ends with one another either by overlapping or by means of a separate connecting piece placed below the then abutting ends.

This manner of manufacturing endless grinding or sanding bands is defective in that the band ends connected with one another in one or the other of the two manners mentioned in the preceding paragraph give rise to disturbances or even interruptions of the grinding work, as the bands are affected and attacked by the work-pieces brought into contact with the abrasive layer or coating in order to be ground thereby, the result being that the bands are destroyed at the place or places of junction of the ends, and the connection is disconnected.

The disadvantages and drawbacks experienced with endless grinding bands of the known kind are completely done away with by my present invention in which the abrasive is applied to bands which are endless from the beginning, having, therefore, no joint, there being manufactured as first stage an endless band (produced, perhaps, by cutting off a piece of suitable axial length from a hose-like fabric), which then is coated with an agglutinant (second stage), hereafter covered with the abrasive (third stage), and finally either left to itself or exposed to moderate heat (fourth stage) in order to become dry.

In order to make my invention more clear, I refer to the accompanying drawings in which Figure 1 is a perspective view of an endless band not yet provided with the abrasive layer; Figure 2 is a cross section through this band; Figure 3 is a view similar to Fig. 1 showing the band provided with the abrasive layer, finished for use; Figure 4 is a cross section through this band; Figure 5 is a side-view of a machine serving for applying the agglutinant to the band; and Figure 6 is a side-view of a machine serving for applying the abrasive to the band, this figure being drawn to a reduced scale relatively to Fig. 5, all as more fully described hereinafter.

The Figures 1, 2, 3, and 4, require obviously no detailing description after the elucidations already given in the introductory part of this specification. But as regards Fig. 5, *b* denotes a receptacle or basin containing the agglutinant, for instance liquid glue, and *c* is a roller dipping into the liquid glue or the like and conveying it to the endless band *d* (such as shown in Fig. 1) which runs over two guide-rolls *e* and *e'* and a tensioning roll *e''*. The two lower rolls are carried by a practically horizontal lever *f* hinged at *f'* to the frame, and the upper roll is carried by a similar lever *g* hinged at *g'* to said frame. Outside their fulcrums *f'* and *g'* the levers *f* and *g* are provided with counterpoises *h* and *h'*, but the lower lever is ordinarily checked by a pin *i* by which it is then coupled to the frame.

The manner of operation of this machine is as follows:

The basin *b* is provided with a sufficient quantity of the liquid agglutinant and the roller *c* is rotated by the cog-wheel gearing *w w'*. The pinion *w* which forms a part of this gearing is driven by any available source of power. The rotation of the cog-wheel *c'* is transmitted to the roll *e* by means of a cog-wheel *w'* whereby the endless band *d* is caused to travel round. While moving in this way it is provided with a layer of the liquid agglutinant by the roller *c*. This having been accomplished the pin *i* is withdrawn, in consequence whereof the levers *f* and *g* are swung upwards by the counterpoises *h* and *h'*, this motion being limited by an abutment *j* co-operating with the righthand-arm of the lever *g*. Owing to said upward motion the gearing between the cog-wheels *w'* and *w'* is interrupted, and the three band-carrying rolls, together with the band, come to a stand-still. The band with its moist coating of the liquid glue or the like is now removed from the rolls and a new one is put on in lieu of it.

The bands are now treated one after another in the apparatus illustrated in Fig. 6 in which they are provided with the abrasive, as well as dried thereafter. *n* denotes a receptacle containing the pulverulent abrasive, *o* is a distributing roll, and *m m'* are rolls receiving the endless band *d*. The rolls are rotated slowly and the abrasive is at the same time distributed uniformly over and upon it. The completely covered bands are then taken off the rolls *m m'*, and are

hung upon stationary rolls α or the like upon which they are left until having become dry, the grinding or sanding bands being then ready for use.

5 I claim:

1. An apparatus for manufacturing endless grinding bands, comprising, in combination: a basin adapted to receive a liquid agglutinant; a roller dipping into said basin, and means for rotating said roller; rolls arranged to receive an endless band and to cause it to contact with a part of the free circumferential surface of the roller; two levers arranged one over the other and having said rolls attached to them and being adapted to be swung in a vertical plane; and means for moving said levers in such a direction that the endless band is moved off the said roller, substantially as described.
- 10 15 20 2. An apparatus for manufacturing endless grinding bands comprising, a supporting frame, an open top liquid agglutinant container, a rotatable roller having a por-

tion of its periphery projecting into the container, a pair of vertically spaced levers pivoted at vertically aligned points to the frame, a pair of horizontally spaced rolls carried by the lower lever in proximity to the roller, an idler roll carried by the upper lever, drive connection between the roller and one of the horizontally spaced rolls, said rolls serving to move a grinding band over the periphery of said roller to effect application of a liquid agglutinant, and means to permit of vertical separation of the levers and grinding band with the rolls from said roller.

3. A structure as specified in claim 2; said means comprising a removable pin interconnecting one free end of the lower lever and the frame, and counterbalancing weights adjacent corresponding ends of the levers remote from said pin.

In witness whereof I have hereunto set my hand.

RICHARD NICKEL.
